DESIGN FOR A KNIFE OR FORK-HANDLE CALLED "ELIZABETHIAN."

The Schedule referred to in these Letters Patent and making part of the same.

TO ALL WHOM IT MAY CONCERN:

Be it known that I, GEORGE WILKINSON, of the city and county of Providence, and State of Rhode Island, have originated a new Design for Articles of Silver and other Metals and Plated Ware, of which the following is a full, clear, and exact description, reference being had to the accompanying specimens or drawings, making part of this specification, that is to say, for a design called the "Elizabethian," for the handle of forks, spoons, other table-ware and implements.

The said handle, as represented in said drawings, has a flat stem, *d*, ornamented on the front side with beads, *s s*, terminating at each end in ornaments, *f*, of the "Elizabethian" order, from which the design derives its name.

On the blade, *B*, there is a field enclosed by an oval bead, *x*, beneath which is a fold of drapery, *e e*, and a bouquet, *n*.

I claim the design for the handles of forks, spoons, &c., substantially as herein represented and described.
